(57) **CLAIM**

I claim the ornamental design for the facial iron, as shown and described.

DESCRIPTION

FIG. 1 is a top perspective view of a facial iron showing my new design.

FIG. 2 is a front elevational view of the facial iron shown in FIG. 1.

FIG. 3 is a rear elevational view of the facial iron shown in FIG. 1.

FIG. 4 is a left side elevational view of the facial iron shown in FIG. 1.

FIG. 5 is a bottom plan view of the facial iron shown in FIG. 1; and,

FIG. 6 is a top plan view of the facial iron shown in FIG. 1.

1 Claim, 2 Drawing SheetsFIG. 1

FIG. 2

FIG. 3

FIG. 4

FIG. 5

FIG. 6
